Primary Examiner — Abraham Bahta(74) *Attorney, Agent, or Firm* — Daniel J. Layden; Brandon J. Lee(57) **CLAIM**

The ornamental design for a trash bag, as shown and described.

DESCRIPTION

FIG. 1 is a front elevation view of the trash bag showing my new design, the back view being identical; and, FIG. 2 is an enlarged detailed view of the encircled portion in FIG. 1, shown for ease of illustration.

The dot-dot-dash line of FIG. 1 merely indicates the upper boundary of the pattern of the trash bag; the area extending above this boundary line is encompassed as part of the claimed design. The trash bag has no appreciable thickness. The shorter broken lines show portions of the trash bag that form no part of the claimed design; thus, the area extending below the lower boundary of the pattern is not part of the claimed design. The longer broken lines indicate the enlarged area of FIG. 1 shown in FIG. 2 and form no part of the claimed design. The dot-dash lines show no specific length and form no part of the claimed design.
